United States Patent Office

Des. 211,010
Patented May 14, 1968

211,010

DRIVE-IN RESTAURANT

William B. Cunningham, Oklahoma City, Okla., assignor
to Burger Train Systems, Inc., Oklahoma City, Okla.

Filed Dec. 12, 1966, Ser. No. 4,991

Term of patent 14 years

(Cl. D13—1)

FIG. 1

FIG. 2

FIG. 3

FIG. 4

FIGURE 1 is a perspective view of a drive-in restaurant showing my new design.

FIGURE 2 is an elevational view thereof;

FIGURE 3 is a top view thereof, and,

FIGURE 4 is a cross-sectional view taken along line 4—4 of FIG. 2.

I claim:

The ornamental design for a drive-in restaurant, substantially as shown and described.
